UNITED STATES PATENT OFFICE

LOUIS DAVIDSON, OF PHILADELPHIA, PENNSYLVANIA

BOILER

Application filed May 16, 1929. Serial No. 363,464.

My invention relates to boilers which are adapted for use for the generation of steam or for the heating of water,—either the steam or the water being employed in such manner and for such purposes as are the hot water and steam produced by boilers of constructions heretofore known and in use.

The objects of the invention are to provide a boiler of simple construction whereby it may be produced at relatively low cost; to provide a boiler having means whereby a wide or large area of heating surface is presented, and to that end the passageway for the heating flame from the heating furnace is of tortuous character; to provide means whereby a relatively large quantity of water may be contained in the boiler and relatively large portions or areas thereof subjected to the heat of the fire in the furnace simultaneously; to provide means of simple construction whereby the water in the boiler is located not only directly above the fire within the furnace of the boiler but also is located in lateral relation thereto; and finally to provide a boiler having a construction of such character that it operates with a high degree of efficiency in proportion to the fuel consumption thereof.

Without mentioning further objects at this point in the description of my invention I shall proceed to a detailed description thereof wherein other objects will be pointed out or else such objects will be apparent from such description.

In order that the invention may be readily understood and its various practical advantages fully appreciated reference should be had to the accompanying drawings, wherein I have illustrated one embodiment of the invention in the form at present preferred by me.

In the drawings:

Fig. 1 is a view in central vertical section taken in a plane extending from front to rear of the boiler;

Fig. 2 is a vertical sectional view taken on the line 2—2 of Fig. 1;

Fig. 3 is a view in elevation of an inside portion of the structure looking toward the right in Fig. 2;

Fig. 4 is a view in perspective showing a couple of the interior elements of the structure in separated relation to each other but ready to be placed in cooperative relation to each other;

Fig. 5 is a view in perspective of two plates in spaced relation to each other, which plates are adapted to be secured by welding or otherwise to the opposite ends of the two members shown in Fig. 4; and

Fig. 6 is a view showing in perspective sheets adapted to be united and placed around the parts shown in Figs. 4 and 5 after the assembly of the latter to form a watertight covering therefor.

In the drawings I have shown at 1 a casting constituting a base for supporting the boiler structure, which casting constitutes a support also for the fire box 2 provided in its lower side or bottom with a grate 3 for supporting the fuel for the boiler. The casting is provided with a door of usual construction, as indicated at 4, through which the ashes falling through the grate 3 may be removed. Although I have indicated means for burning solid fuel, it will be understood that a suitable fluid consisting of either a gas or a liquid may be employed as the heating means.

The upper side of the casting 1 in adjoining relation to the peripheral edge thereof is provided with a channel as indicated at 5, which constitutes a seat for the lower edge portions of the side and end portions of the boiler structure.

The boiler comprises interior co-operating and complementary members A and B. The member A is provided with a horizontal bottom plate portion 10 the front end of which in adjoining relation to the front of the boiler structure is provided with a depending flange portion 11 which extends into the channel 5 and is located in engagement with the inner wall thereof, as indicated at the lefthand side of Fig. 1 of the drawings. The depending flange portion 11 is provided with an opening 12 in line or in registry with an opening 13 provided in the parallel outer front cover plate 14 of the boiler structure. The opening thus provided is provided with a frame

or lining, as indicated at 15, which closes the chamber between the plate 14 and the flange portion 11 to render the said chamber water-tight. The passageway provided by the openings 12 and 13 is adapted to be closed by means of a door, indicated generally at 16.

The bottom plate portion 10 of the member A at its rear end opposite the flange 11 is provided with an upwardly extending portion 17 which terminates in a reversely extending horizontal narrow portion 18 from the inner edge of which extends downwardly a portion 19 in parallel relation to the portion 17. The portions 17, 18, and 19 form an elongated hollow leg portion, which I shall designate as a whole at 20. The plate is continued to form additional upwardly projecting hollow elongated leg-like portions 21 and 22. All of these leg-like portions, as well as the space 23, are adapted to receive and hold water. The plate is continued toward the front of the boiler from the lower edge of the front side of the portion 22 and is then extended upwardly, as indicated at 25, and then rearwardly, as indicated at 26, in a plane substantially parallel with the plane of the portion 10. The relationship of all of these parts of the member A as above described, is most clearly indicated in Figs. 1 and 4 of the drawings. The member B is of a construction similar to that of the member A, except that the similar parts are located in reverse relation to their location in the member A. The member B comprises a bottom horizontal plate portion 30 having depending elongated leg-like hollow portions 31, 32, and 33 similar to the portions 20, 21, and 22 of the member A. The rear end of the plate portion 30 terminates in a depending flange-like portion 34 which is located at the back of the boiler structure in parallel relation to the rear outside plate 35 of the said structure. The front side of the portion 31 extends upwardly to a plane above the plate portion 30 and then is extended to the rear, as indicated at 36, and terminates in an upwardly extending narrow flange portion 37 having a rectangular-shaped opening 38 therein. The said opening may be of any other shape which may be preferred. When the two members A and B are assembled as indicated in Figs. 1 to 3 of the drawings it will be noted that the horizontal portions 30 and 36 and the portions 31, 32, and 33 of the member B are located in intermediate relation to the corresponding portions of the member A; that is to say, the portion 36 is located underneath and in spaced relation to the portion 26, and the portions 31, 32, and 33 are located in spaced overlapped relation to the portions 22, 21, and 20. By thus positioning the members A and B and relating the portions thereof to each other as described I have provided not only a tortuous passageway for the flames of the fire which may be located in the fur-

nace as indicated by the arrows 40, but I have also provided a large area of boiler surface to which the heat is applied, whereby a relatively large amount of the flame of the furnace fire is rendered effective for heat-producing purposes.

A tubular member 41 of proper shape is connected at one end within the opening 38 and at its opposite end within an opening 42 within the rear side 35 of the boiler structure. A flue, a portion of which is indicated at 43, is connected within the outer end of the tubular member 41 for conveying away from the boiler the gases of combustion. Although the flue is connected in the construction illustrated with the rear wall of the boiler structure it is to be understood that the gases of combustion may be removed from some other portion of the boiler structure without departing from my invention.

For the purpose of uniting the members A and B I have provided side plates 45 and 46 which are secured to the opposite ends of the said members A and B by welding, brazing, or by any other method or means by which the connection may be rendered water and steam-tight. These plates 45 and 46 are provided respectively with openings 47 which are in communication with the opposite ends of the spaces provided by the portion 31, 32, and 33, and by the spaced relation of the plate 36 to the plate portion 30 of the member B. The said plates are also provided with similar openings 48 which are in communication with the opposite ends of corresponding openings or chambers in the member A. For the purpose of inclosing the plates 45 and 46 I have provided a bent plate C, including a top portion 50 and side portions 51 and 52. When the latter is placed in position its opposite ends are located between the parallel front and rear plates 14 and 35 and are secured thereto, as indicated in Figs. 1 and 2 of the drawings, by welding, brazing or otherwise. As already indicated, the plates 14 and 35 are spaced from the front and rear end portions of the members A and B. Likewise the side portions 51 and 52 of the bent plate C are spaced from the plates 45 and 46 previously referred to. This spaced relation is clearly shown in Fig. 2 of the drawings. The plates 45 and 46, which are secured to the opposite ends of the members A and B as heretofore pointed out, are connected to the adjoining sides 51 and 52 of the bent plate C by means of interposed metal pieces 55, the opposite ends of the latter being connected to the said plates by spot-welding or otherwise, as may be preferred. Likewise the portions 11 and 25 of the member A and the portions 34 and 37 of the member B may be secured to the front and rear plates 14 and 35 by means of similar pieces 56.

For the purpose of providing means whereby the space between the members A and B

may be cleaned out I have provided the plates 45 and 46 with openings 57 and 58 which, in the assembled structure, are located in opposed relation to similar openings 59 and 60 in the opposite sides 51 and 52 of the bent plate C. Short tubular members 61 are located between the plate 45 and the portion 51 of the bent plate C with their opposite ends secured in the openings 57 and 59. Only one of these tubular members 61 is shown, such showing being made in Fig. 2. Similar hollow members 62 are provided between the plate 46 and the portion 52 of the bent plate C with their opposite ends secured in the openings 58 and 60. Only one of the tubular members 62 is shown, such showing being made in Fig. 2 of the drawings. The openings through these tubular members 61 and 62 are adapted to be closed by means of doors 63, the said doors being clamped and held in position by means of nuts 64 provided detachably upon the outer ends of bolts 65. To permit the cleaning out of the space between the plate portions 26 and 36 of the members A and B I have provided the openings 66 and 66' through the plate 14 and the adjoining portion 25 of the member A, which openings are located in registry with each other. The opposite ends of a tubular member 67 are secured in these openings. The outer end of the said tubular member is closed by means of a door or closure 67' which is adapted to be held in closed position by means of holdings means 67'' of known construction. The tubular member 67 constitutes additional supporting and bracing means between the plate 14 and the member A, and likewise the tubular members 61 and 62 constitute additional supporting and bracing means between the plates 45 and 46 and the portions 51 and 52 of the bent plate C.

It may be noted that the metal pieces 56 and the connections at 41 constitute the means for supporting the member B in fixed spaced relation to the member A.

The lower edges of the depending flange portions 11 and 34 of the members A and B, the lower edges of the plates 14 and 35, the lower edges of the plates 45 and 46, and the lower edges of the sides 51 and 52 of the bent plate 50 are located within the seat 5 provided in the upper outer edge portion of the base 1, as above set forth. In order to close the lower sides of the spaces between these various plates, which may be located in parallel relation to each other, the lower edges of the said plates rest upon and have hermetically sealed connection with a narrow plate 68 which rests upon the bottom of the groove or seat 5. Preferably the plate 68 is connected to the lower edges of the plates mentioned by being welded or brazed thereto, but any preferred form of connection may be employed.

For the purpose of conveying either water

or steam from the boiler, whichever may be desired, I have provided an outlet conduit 70 having connection through an opening 71 in the portion 50 of the bent plate C. The outflow of fluid, whether water or steam, through the said outlet pipe 70 may be controlled by means of a valve 72. After the water or steam which is conveyed from the boiler outwardly through the pipe 70 has performed its function and given up its heat, as for example, in the heating of the radiators of a heating system, the cooled water (the steam having been converted into water by condensation) should be returned to the boiler, as is the usual practice, and I have indicated at 72' the end portion of the return pipe for returning such water to the boiler.

In order to provide for the safety of the boiler I employ a blow-out valve at 73 of any usual construction.

In order to control the burning of the fuel in the fire box or furnace I have provided a damper-control valve at 74 of known construction, the movable part of the valve being provided with an arm 75 from which a chain, cord or the like extends to an arm or lever connection to the damper. If the fire in the fire box is burning with such energy as to create a pressure either of steam or hot water greater than a predetermined maximum, the valve at 74 would be operated to effect movement of the arm 75 to thereby effect movement of the damper, neither the latter nor the chain or cord connection between the same and the lever being shown.

It will be seen that by my invention I have provided a boiler construction of sheet metal plates, preferably steel, the abutting edges of which are secured together by means of welding, brazing or in any other preferred way.

It also will be seen that I have provided a construction in which the heat generated by the burning of the fuel in the fire box is applied or caused to contact with the relatively

very wide areas of the interior of the boiler structure, which areas are in juxtaposition to the water within the boiler which is to be heated. In the construction as illustrated in the embodiment of my invention I have pro-

vided a tubular passageway by which the heating flame and hot gases of combustion are conducted through a relatively long distance, in contact with parts of the structure within which are included portions of water or the like to be heated. The latter portion

of the passageway for the flame and hot gases of combustion is so related to the structure as to adapt it for contact with portions of the liquid within the boiler to be heated, where-

by a maximum of the heat generated by the burning of the fuel within the fire box is utilized in the heating of the liquid.

The simplicity of the structure embodying my invention is apparent, and it also is believed to be apparent that the structure

may be constructed or built at a relatively very low cost.

The device is particularly well adapted for the supplying of hot water or steam for the heating of houses, but it is not limited to such use but is capable of general application for the production of heated water or steam for use for any other purposes for which those substances may be employed.

For the purpose of conveying water to the boiler as the same may be needed I have provided a valve-controlled inlet pipe 76, indicated in Fig. 2 of the drawings, and for the purpose of draining the water from the boiler I have provided a valve-controlled outlet pipe 77, also indicated in said Fig. 2.

In the construction as illustrated it will be noted that the liquid fluid extends to or substantially to the top of the boiler, which is substantially the relationship existing between the liquid and the boiler when the latter is to be employed for the supplying of hot water; but if the boiler is to be employed for the supplying of steam, the water should occupy a portion only of the interior boiler chamber, leaving the upper portion free to collect and hold steam which may be supplied through the pipe 70.

Having thus described my invention, what I claim and desire to secure by Letters Patent is:

1. A boiler of the character described, comprising sheet metal plates secured together in edge-to-edge relation to each other to form a chamber, sheet metal members located within and supported upon the said sheet metal plates, said members consisting of plates bent transversely at an intermediate portion thereof, and the opposite sides of the said bent portions occupying positions in parallel spaced relation to each other and one of the sides of each of the said members being provided with hollow portions which project laterally therefrom, the spaces thus produced being adapted to hold a liquid and each of the said members terminating at one end in a depending flange and one of the said members having a horizontally extending portion located above and in parallel relation to the top side of the other of said members, the projections extending in opposite directions and in alternate spaced relation with respect to each other thereby forming a tortuous passageway through which the flames and the gases of combustion travel.

2. A boiler of the character described, comprising sheet metal plates secured together in edge-to-edge relation to each other to form a chamber, sheet metal members located within and supported upon the said sheet metal plates, each of the said members consisting of plates bent transversely at an intermediate portion thereof, and the opposite sides of the said bent portions occupying

ing positions in parallel spaced relation to each other and one of the sides of each of the said members being provided with hollow portions which project laterally therefrom, the spaces thus produced being adapted to hold a liquid and each of the said members terminating at one end in a depending flange and one of the said members having a horizontally extending portion located above and in parallel relation to the top side of the other of said members, the projections from the said members extending in opposite directions and in alternate spaced relation with respect to each other thereby forming a tortuous passageway through which the flames and the gases of combustion travel, and a fuel-burning means located directly underneath the said two members.

3. A boiler of the character described, comprising interior metal plate members each of which comprises a narrow chamber extending horizontally of the boiler, the said chambers being formed by parallel portions of parts of each member, hollow projections extending laterally from one side of each of the said members, said projections extending in opposite directions and in parallel spaced overlapping relation to each other and each of the said members being provided with a depending flange portion located in spaced relation to the exterior portion of the boiler, and one of the said members provided with an intermediate portion which extends in parallel relation to and adjoining an exterior wall portion of the boiler, and a horizontally extending portion which is located above and in spaced relation to the uppermost of the said two members.

4. A boiler of the character described, comprising interior metal plate members each of which comprises a narrow chamber extending horizontally of the boiler, the said chambers being formed by parallel portions of parts of each member, hollow projections extending laterally from one side of each of the said members, said projections extending in opposite directions and in parallel spaced overlapping relation to each other and each of the said members being provided with a depending flange portion located in spaced relation to the exterior portion of the boiler, and one of the said members provided with an intermediate portion which extends in parallel relation to and adjoining an exterior wall portion of the boiler, a horizontally extending portion which is located above and in spaced relation to the uppermost of the said two members, and a fuel-burning means located directly underneath the said members.

5. A boiler comprising an exterior of sheet metal plates united at their edges to form an interior chamber, two liquid-receiving members located within said chamber, said members each comprising parallel portions ar-

ranged in spaced relation to each other and extending transversely and horizontally of the said boiler and said members being provided with hollow elongated projections extending therefrom, in opposite directions and in alternate spaced relation to each other and cooperating with each other and with the main portions of the said members to form a tortuous passageway extending across the said boiler, and each of said members having at one side thereof a depending flange portion located in spaced relation to an adjoining portion of the outer wall of the boiler and one of the said members having an upwardly extending intermediate portion arranged in parallel spaced relation to a portion of the outer adjoining wall and a horizontally extending portion located in spaced relation to and above the upper of said members, plates secured to the opposite ends of said members which plates are provided with openings in registry with the interior chambers of the said members, and means for rigidly connecting the said members and the said plates with adjoining portions of the exterior wall structure of the boiler.

6. A boiler comprising an exterior of sheet metal plates united at their edges to form an interior chamber, two liquid-receiving members located within said chamber, said members each comprising parallel portions arranged in spaced relation to each other and extending transversely and horizontally of the said boiler and said members being provided with hollow elongated projections extending therefrom, in opposite directions and in alternate spaced relation to each other and cooperating with each other and with the main portions of the said members to form a tortuous passageway extending across the said boiler, and each of said members having at one side thereof a depending flange portion located in spaced relation to an adjoining portion of the outer wall of the boiler and one of the said members having an upwardly extending intermediate portion arranged in parallel spaced relation to a portion of the outer adjoining wall and a horizontally extending portion located in spaced relation to and above the upper of said members, plates secured to the opposite ends of said members which plates are provided with openings in registry with the interior chambers of the said members, means for rigidly connecting the said members and the said plates with adjoining portions of the exterior wall structure of the boiler, and means for closing the lower open ends of the spaces between the exterior wall of the boiler and the depending flange portions of the said members and of the plates secured to the opposite ends of the latter.

7. A boiler comprising interiorly thereof two members adapted to hold water to be heated by the heat generated from burning

fuel, each of which members consists of plates in spaced relation to each other to provide a chamber therein and each of the said members having hollow projections extending therefrom in substantially right angular relation thereto and each of the said members having a depending flange portion which extends from one side thereof in parallel relation to the adjoining portion of an exterior wall of the said boiler and one of the said members having an intermediate portion located in parallel relation to the adjoining portion of an exterior wall of the said boiler and also having a portion extending in parallel relation to the said two parallel plate portions thereof, and means for supporting the said members with the parallel plates of one in parallel relation to the parallel plates of the other member and with the lateral projections thereof extending in opposite directions and in spaced overlapping relation to each other.

8. A boiler comprising interiorly thereof two members which extend across the said boiler and are adapted to hold water to be heated by the heat generated from burning fuel, each of which members consists of plates in spaced relation to each other to provide a chamber therein and each of the said members having hollow projections extending therefrom in substantially right angular relation thereto and each of the said members having a depending flange portion which extends from one side thereof in parallel relation to the adjoining portion of an exterior wall of the said boiler and one of the said members having an intermediate portion located in parallel relation to the adjoining portion of an exterior wall of the said boiler and also having a portion extending in parallel relation to the said two parallel plate portions thereof, means for supporting the said members with the parallel plates of one in parallel relation to the parallel plates of the other member and with the lateral projections thereof extending in opposite directions and in spaced overlapping relation to each other, and fuel-burning means located underneath the said members, the space between the two parallel portions of the said members and between the projections extending therefrom in overlapped relation to each other constituting a tortuous passageway for the flames and gases of combustion generated by the burning fuel.

9. A boiler comprising an exterior wall inclosing a chamber, members located within said chamber, said members comprising liquid-holding chambers and each of the said members having a depending flange portion located in spaced parallel relation to an adjoining portion of the exterior wall of said boiler and one of the said members having an upwardly extending intermediate portion arranged in a plane substantially coin-

incident with the plane of the flange portion thereof and being located in spaced substantially parallel relation to an adjoining wall portion, plates secured to the opposite ends of said members, which plates are located in spaced substantially parallel relation to the adjoining exterior wall portions, means for rigidly connecting the said flange portions and intermediate portion of the said members and the said plates to the said adjoining portions of the exterior wall, and means for closing the lower ends of the spaces between the said flange portions and the said plates and the exterior wall of the said boiler.

In testimony that I claim the foregoing as my invention I have hereunto signed my name this 10th day of May, A. D. 1929.

LOUIS DAVIDSON.
